UNITED STATES PATENT OFFICE

WILLIAM E. TAYLOR, OF EAST ORANGE, NEW JERSEY, ASSIGNEE TO AMERICAN CAN COMPANY, OF NEW YORK, N. Y., A CORPORATION OF NEW JERSEY

SCORING MACHINE

Application filed May 22, 1929. Serial No. 365,019.

The present invention relates to machines for forming score lines in blanks for tearing strip containers, and the like, and has particular reference to improvement in scoring roller construction.

5 The invention contemplates the provision of a scoring roller consisting of more than one part, such a construction permitting easier and more accurate machining of the 10 scoring edges thereof. These parts are preferably adjustably related one to the other thereby providing flexibility of design in the score pattern produced. An improved scoring roller embodying the present invention 15 may be employed in a type of machine cutting both parallel score lines setting off a tearing strip and diagonal score lines arranged adjacent the parallel lines, an illustration of such a machine being found in United States 20 Letters Patent 1,623,223, issued April 5th, 1927 for improvements in scoring machine, invented by Magnus E. Widell.

The principal object of the present invention is the provision of an improved scoring roller for use in connection with a scoring apparatus for cutting composite score lines in a blank of sheet material, the composite score lines being produced by a plurality of scoring rollers each scoring roller 25 providing a characteristic pattern of score lines.

An important object of the invention is the provision of an improved scoring roller for cutting diagonal score lines in a blank of sheet material, such a roller being formed in 30 two parts to permit easy manufacture.

A further important object of the present invention is the provision of an improved scoring roller formed in two parts, each part 35 of which may be adjustably positioned relative to the other, each adjusted setting producing its individual score pattern in the blank being scored.

An important object of the invention is the 40 provision of an improved scoring roller provided with two sets of scoring dies each set cooperating with the other to produce a scoring pattern which may be altered at will by changing the relative position of the two sets 45 of scoring dies.

Numerous other objects and advantages of the invention will be apparent as it is better understood from the following description, which, taken in connection with the accompanying drawings, discloses a preferred embodiment thereof.

55 Referring to the drawings:

Figure 1 is a side elevation of the operating parts of a machine in which the present invention is embodied.

60 Fig. 2 is a fragmentary front elevation of the improved scoring roller showing its relative position to other parts of the scoring apparatus, parts being illustrated in section.

65 Fig. 3 is a view similar to Fig. 2 illustrating a different adjusted position of the improved scoring roller parts.

70 Fig. 4 is a transverse sectional view taken substantially along line 4—4 of Fig. 3, parts being illustrated in elevation.

75 Fig. 5 is a fragmentary view of a blank after scoring by the scoring roller of the present invention when adjusted to form one certain pattern of scoring.

Fig. 6 is a view similar to Fig. 5 illustrating a different scoring pattern.

75 The machine embodying the present invention comprises a standard 21 (Fig. 1) adapted to rest upon the floor and to carry a supporting frame 22 in which the operating parts of the scoring apparatus are located. Supporting frame 22 carries a feeding table 23 extending in a substantially horizontal plane across the front of the apparatus. Blanks 24 preferably of sheet material, as 80 for example tinplate, are placed upon the upper surface of table 23 in any suitable manner and are moved along a guide 25 carried by the table 23.

85 A plurality of feeding rollers 26 (Figs. 1, 2 and 4) are mounted upon and rotated by horizontal shafts 27 journaled in bearings 28 formed in the supporting frame 22. The feeding rollers 26 extend through openings 29 formed in table 23 and project slightly 90 above the upper surface of the table.

95 A plurality of scoring rollers are mounted above the feeding table 23 (Fig. 1) in tandem relation. Said scoring rollers in the present embodiment comprise a parallel line 100

roller 31 carried by and rotating with a shaft 32 journaled in the frame 22, a scoring roller 33 mounted upon and carried by a horizontal roller shaft 34 (Fig. 4) also mounted for rotation in the frame 22 and a flattening 5 roller 35 mounted upon and rotating with a horizontal shaft 36 journaled in frame 22. The shafts 32, 34 and 36 are rotated in synchronism with the shafts 27 in any usual or preferred manner.

10 Roller 31 is positioned directly above the first feeding roller 26 and these two rollers cooperate to advance the blank 24 along the surface of the feeding table 23 and toward the left as viewed in Fig. 1. Scoring roller 15 33 is positioned directly above the second feeding roller 26 and these two rollers cooperate to further advance the blank through the apparatus. Roller 35, in turn, 20 is positioned directly above the third feeding roller 26 and these two rollers cooperate to further advance the blank over the feeding table 23 and to discharge it from the apparatus.

25 Roller 31 is provided with scoring edges for engaging the upper surface of the blank 24 as it is passing over the first feeding roller 26 and these scoring edges cut two parallel score lines 37 (Fig. 5) in the blank 24. 30 These lines bound a tearing strip 38 which is thereby set off in the blank 24. Scoring roller 33 is provided with scoring edges, which engage the upper surface of blank 24 as it passes over the second feeding roller 35 26 and which score a series of diagonal lines 39 and 41 positioned inside of the bounding lines 37. Roller 35 is provided with a smooth periphery which flattens and smooths any irregularities in the previously scored lines 40 37, 39 and 41 by engaging the upper surface of the blank 24 as it passes over the third feeding roller 26.

Scoring roller 33 (Figs. 3 and 4) comprises a roller body 42 keyed at 43 to the 45 forward end of shaft 34 and a roller head 44 mounted on the shaft 34 forward of the body 42. Roller head 44 is connected with the body 42, a side wall 45 of the head engaging a side wall 46 of the roller body. 50 The roller parts 42 and 44 are held in longitudinal position upon the roller shaft 34, being firmly clamped between a shoulder 47 formed on shaft 34 and a washer 48 held by a bolt 49 threadedly secured to the end of 55 the shaft 34.

Roller body 42 is provided with a scoring die consisting of a plurality of parallel projecting ridges 51 preferably arranged adjacent the wall 46 and extending diagonally 60 on the surface of the body, said ridges 51 projecting outwardly from the periphery thereof. Roller head 44 is provided with a similar scoring die consisting of a plurality of parallel projecting ridges 52 preferably 65 arranged adjacent the wall 45 and extending

diagonally on the surface of the head and projecting outwardly therefrom. The scoring dies 51 and 52 upon contacting the upper surface of blank 24 (Fig. 4) press the blank firmly against the feeding roller 26 and score lines 39 and 41 as the scoring roller rotates in synchronism with the feeding roller. A feeding ring or rubber 53 is positioned within a peripheral groove 54 formed in the roller head 44 and this frictionally engages the blank 24 and assists in its movement along the feeding table 23.

It will be evident that varying degrees of angularity between the scoring dies 51 and 52 may be employed to meet conditions 70 pertaining to the individual container to be opened, or the ridges 51 may be disposed parallel to ridges 52 instead of an acute angle as shown and such an arrangement will provide parallel score lines 39 and 41 in the blank. Such a system of scoring is advantageously adapted to a container having a single bounding line 37 and a single line of 75 tearing instead of the parallel lines shown.

80 To obtain the best results in scoring, projecting ridges 51 and 52 must be accurately made and properly sharpened. Where the ends of such cutting dies come together or lay closely adjacent each other as in the scoring 85 illustrated this die manufacture with the one piece rollers now in use, becomes very difficult. It is particularly difficult to machine die parts when an acute angle is formed between them as in the case of the diagonal 90 score lines illustrated. By mounting ridges 95 51 and 52 on separable members as in this present invention this machining operation 100 is greatly simplified and greater accuracy of parts is provided.

Provision is made for locating the roller 105 head 44 in one of several definite positions relative to the roller body 42. There is used for this purpose a dowel pin 55 carried by the roller head 44 and projecting beyond its wall 45. Pin 55 is positioned within one of 110 three bores 56, 57 and 58, which are at the same distance from the center of shaft 34 but which are spaced angularly at different 115 distances from each other. In this angular spacing the bore 57 is slightly in excess of 120° from the bore 56 and the bore 58 is slightly less than 120° distanced from the bore 56 as indicated in Fig. 3.

120 By placing pin 55 in the different bores the scoring dies 51 and 52 are located at different 125 relative positions longitudinal of the tearing strip 38 and this effects the scoring pattern formed by the scoring dies. For example, when the roller head 44 is arranged with its pin 55 in bore 56 of the body 42 (Figs. 3 and 125 4) the resulting scoring pattern involving the lines 39 and 41 forms a diagonal stagger layout as illustrated in Fig. 6. When roller head 44 is shifted to position its pin 55 in bore 57 (Fig. 2) the resulting score pattern 130

on the blank 24 is a herringbone score pattern, such as is illustrated in Fig. 5. In like manner, positioning pin 55 within bore 58 will produce a scoring roller whose scoring action will result in a scoring pattern similar to that shown in Fig. 6 but differing in the relative positions of the score lines 39 and 41.

This shifting of head 44 relative to body 42 is permitted by removal of bolt 49 and washer 10 48 from their clamping position at which time head 44 is slid on shaft 34 sufficiently to withdraw pin 55 from one bore and to insert it into another the head 44 at such a time being turned on shaft 34 into the required position. When located with pin 55 in place, washer 48 and bolt 49 are restored to clamp the parts together. As a further insurance against slipping between the roller parts, 20 there are provided several bolts 61 threaded- 25 ly engaging the body 42 and passing through elongated shouldered slots 62 formed in the roller head 44. The head of each bolt 61 when screwed into clamping position engages a shoulder 63 formed in the head about each slot. The elongated form of slots 62 permit arrangement of the bolts 61 regardless of the relative position of roller parts 42 and 43.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In an apparatus for scoring blanks for tearing strip containers, the combination of a feeding table, feeding rollers for advancing a blank over said table, a scoring roller disposed above one of said feeding rollers and having means for scoring parallel bounding lines of the tearing strip in said blank, a two-part scoring roller embodying a roller body and a roller head disposed above another of said feeding rollers, and means carried by said body and said head for scoring diagonal lines between said parallel lines.

2. In an apparatus for scoring blanks for tearing strip containers, the combination of a feeding table, feeding rollers for advancing a blank over said table, a scoring roller disposed above one of said feeding rollers and having means for scoring parallel bounding lines of the tearing strip in said blank, a two-part scoring roller embodying a roller body and a roller head disposed above another of said feeding rollers, means carried by said roller body for scoring diagonal lines adjacent one of said parallel bounding lines, and means carried by said roller head for scoring

associated diagonal lines adjacent the other of said parallel bounding lines.

3. In an apparatus for scoring blanks for tearing strip containers, the combination of a supporting frame, a feeding roller rotatably mounted in said frame for advancing a blank through the machine, a shaft rotatably mounted in said frame above said feeding roller, a two-part scoring roller mounted on said shaft and disposed above said feeding roller, said scoring roller embodying a roller body and a roller head and scoring edges carried in part by said body and in part by said head for scoring diagonal lines in said blank, said scoring edges being arranged diagonally within the circumferential plane of said scoring roller.

4. In an apparatus for scoring blanks for tearing strip containers, the combination of a supporting frame, a feeding roller rotatably mounted in said frame for advancing a blank through the machine, a shaft rotatably mounted in said frame above said feeding roller, a two-part scoring roller mounted on said shaft and disposed above said feeding roller, said scoring roller embodying a roller body secured to said shaft and a roller head carried on said shaft in one of several scoring positions relative to said roller body, and means carried in part by said body and in part by said head for scoring diagonal lines in said blank, each of said roller body and head positions providing a distinct and individual relationship between parts of the diagonal score lines produced by said scoring means.

5. In an apparatus for scoring blanks for tearing strip containers, the combination of a supporting frame, a feeding roller rotatably mounted in said frame for advancing a blank through the machine, a shaft rotatably mounted in said frame above said feeding roller, a two-part scoring roller mounted on said shaft and disposed above said feeding roller, said scoring roller embodying a roller body secured to said shaft and a roller head carried on said shaft in one of several scoring positions relative to said roller body, means carried by said body for scoring diagonal lines along one side of the tearing strip in the blank, means carried by said head for scoring diagonal lines along the opposite side of said tearing strip, and devices for locating and clamping said scoring head in its scoring position.

6. A two-part scoring roller for a blank scoring apparatus, comprising in combination a roller body, a roller head connected with said body and having one side wall in engagement with a side wall of the body, a scoring die carried by said body consisting of a plurality of projecting ridges extending diagonally adjacent the edge of the engaging wall of said body, and a scoring die carried by said head consisting of a plurality of

projecting ridges extending diagonally adjacent the edge of the engaging wall of said head, the scoring dies cooperating to cut a score pattern of diagonal lines in a blank passing through the scoring apparatus.

5 7. A two-part scoring roller for a blank scoring apparatus, comprising in combination a roller body, a roller head connected with said body and having one side wall in engagement with a side wall of the body, a scoring die carried by said body consisting of a plurality of projecting ridges extending diagonally adjacent the edge of the engaging wall of said body, and a scoring die carried by said head consisting of a plurality of projecting ridges extending diagonally adjacent the edge of the engaging wall of said head, and at an angle to the diagonal ridges on said body, the scoring dies cooperating to cut a herringbone score pattern of diagonal lines in a blank passing through the scoring apparatus.

8. A two-part scoring roller for a blank scoring apparatus, comprising in combination a roller body, a roller head connected with said body and having one side wall in engagement with a side wall of the body, a scoring die carried by said body adjacent the edge of its engaging wall, a scoring die carried by said head adjacent the edge of its engaging wall, the scoring dies cooperating to cut a score pattern in a blank passing through the scoring apparatus, and locating and clamping devices for holding said roller head in one of several connected positions with said roller body, the relative position of the roller head and the roller body determining the score pattern cut in the blank.
